Primary Examiner — T Chase Nelson(74) *Attorney, Agent, or Firm* — CANTOR COLBURN LLP(57) **CLAIM**

The ornamental design for a spectacle case, as shown and described.

DESCRIPTION

FIG. 1 is a front perspective view of a spectacle case, showing our new design;

FIG. 2 is a rear elevation perspective view thereof;

FIG. 3 is a front elevation view thereof;

FIG. 4 is a top plan view thereof;

FIG. 5 is a bottom plan view thereof; and,

FIG. 6 is a right side elevation view thereof, the left side being a mirror image thereof.

The broken lines show portions of the spectacle case that form no part of the claimed design.
